UNITED STATES PATENT OFFICE

HAROLD O. HILL, OF ASPINWALL, PENNSYLVANIA, ASSIGNOR TO RITER-CONLEY MANUFACTURING COMPANY, OF PITTSBURGH, PENNSYLVANIA, A CORPORATION OF PENNSYLVANIA

TOWER CONSTRUCTION

Application filed February 27, 1929. Serial No. 343,075.

This invention relates to improvements in structural steel towers of the type used in supporting high tension transmission lines, telegraph wires, and the like, and more particularly to new and improved supporting or foundation means employed for erecting the towers on unlevel ground, and commercially known as leg extensions for towers.

Heretofore, various constructions have been employed for erecting towers on hill-sides or unlevel ground in order to avoid the great expense involved in leveling the ground to provide the proper foundations. For instance, concrete piers have been employed; also, in some cases, structural steel members have been utilized. In the latter instance, however, the said leg extensions have been used only where the tower proper or the base thereof has included horizontal struts connecting the corner posts or legs of the tower; the said extensions being connected with the horizontal struts and braced from the tower proper or other superstructure.

It is an object of the present invention to provide a simple and efficient leg extension for towers of the type specified comprising a construction that may be utilized without the employment of the horizontal struts or other super-structure at the base of the tower, and embodying means whereby the leg extensions are braced from the ground, as distinguished from being braced from the tower or by structural members attached to the tower.

Further objects of the present invention are, to provide a new and improved stub construction that may be utilized for erecting towers on unlevel ground without the necessity of the usual excavating and back-filling; to provide an extension leg stub construction including standardized members that may be fabricated at the shop without predetermination of the exact level conditions of the ground at the tower site, and kept on hand by the tower erector and utilized when needed; and to provide a simple and efficient stub construction that may be placed in the ground prior to erecting the tower and upon which the tower may be positioned at a minimum of expense and labor.

In the accompanying drawings, which illustrate an application of my invention:

Fig. 1 is a side elevational view, showing a base portion of a tower mounted on the stub construction or leg extension embodying my invention;

Fig. 2, a side elevational view of the stub construction taken at right angles to the view of the stub of Fig. 1; and

Fig. 3, a horizontal sectional view taken on line III—III of Fig. 1.

Referring to the drawings, A designates generally a portion of a transmission tower construction of rectangular shape in cross section and including corner members or legs 5 and diagonals 6, the lowermost diagonals of the tower being secured to the lower ends of the legs 5 or to the corner members at the base of the tower proper and to horizontally disposed members 7, the lowermost of the members 7 being positioned well above the base of the tower or the lower ends of the legs 5.

It is very desirable to provide a tower construction of a character that eliminates members close to the ground line, such for instance, as horizontal struts extending from corner to corner and disposed close to the ground line, as such members prevent the cultivation of the ground within the tower base; and in my construction, such members are dispensed with.

The leg extensions of the present invention include a stub construction embodying certain features of stub construction shown in United States Letters Patent granted to me January 1, 1924, No. 1,479,180. In the present case, however, I have provided an adjustable stub construction including a plurality of telescoping members having cooperating means for adjustably securing said members together and to the lower ends of the legs 5 of the tower.

The leg extension or stub construction, as illustrated and as preferred, is designated generally as B and is designed to be connected with a leg of the base portion of the tower. The construction includes a grillage 8 made up of a plurality of cross members 9 connected by angle members 10, centrally disposed channels 11, and a short section of 103

an I-beam 12, to which the lower end of the stub proper is attached by means of bolts.

The adjustable leg extension or stub includes a short section of angle bar 13 having a slight bend at its lower end, a relatively long intermediate section 14, and an upper section 15, the latter being designed to have its upper end connected with the lower end of the leg 5. 16, 17 and 18 designate lap splices or overlapping portions of the stub sections and tower leg. Each of the sections 13, 14 and 15, as well as the lower end of the leg 5, are formed with closely spaced openings through which bolts or fastening means are passed for adjustably securing said members together, said apertures being designated *a*, *b*, *c* and *d*, respectively. It will be noted that the leg extension or stub comprises a plurality of adjustable telescoping members of such character that the extension leg may be assembled to meet varying conditions of ground elevation.

The form of stub shown at the right of Fig. 1 is not a leg extension, and hence does not have the intermediate section 14 of the leg extension shown at the left of said figure. In each form of stub, I preferably attach to one of the sections a stabilizer 19 comprising a longitudinally extending angular member, functioning to resist strains in one direction and bending moments in another direction.

Secured to the upper section 15 of the leg extension and attached thereto, preferably near the lower end of the leg 5 of the tower, I provide a ground brace 20 including, as shown, a plurality of telescoping angle bar sections 21 and 22 having a lap splice 23, each formed with holes *e* for the reception of bolts. The lower section 22 of the said ground brace is connected at its lower end to an anchor member 24, and the upper end of section 21 is connected to the section 15 of the stub or leg extension by means of an angular plate 25.

In practice, and as shown, I employ two ground or shear braces 20. Said braces, it will be noted, brace the leg extension from the ground and by this means I dispense with any bracing from the tower or other structural elements connected with the tower proper for stabilizing or bracing the leg extension. These braces 20 extend inwardly and downwardly into the ground from the upper end of the leg extension, and may be embedded to any desired depth in the ground.

I claim:

1. The combination with a tower construction free of horizontal struts adjacent the base of the tower and having a leg, of a leg extension comprising a stub including a plurality of adjustable members secured to the tower only by said leg, and a ground brace for the stub having an end embedded in the upper end of the ground and an end attached to the stub above the ground level.

2. The combination with a tower construction free of horizontal struts adjacent the base of the tower and having a leg, of a leg extension comprising a stub including a plurality of adjustable members secured to the tower only by said leg, and a plurality of ground braces having ends embedded in the ground and ends attached to the upper end of the stub above the ground, said ground braces each including a plurality of adjustable members.

3. The combination with a tower construction free of horizontal struts adjacent the base of the tower and having a leg, of a leg extension comprising a stub having anchoring means at its lower end and attached to the leg at its upper end, said extension including a plurality of adjustable members, and a ground brace attached to the stub, said stub and brace having portions embedded in the ground and portions projecting above the ground.

4. The combination with a tower proper comprising a plurality of legs, diagonal bracing above the lower ends of the legs connecting the legs, said tower adjacent the lower ends of the legs being free of other structural members entering into its construction, and an independent leg extension detachably secured to a tower leg, said extension comprising a stub including a plurality of adjustable members with the upper member attached to a tower leg, and a ground brace for the extension having a portion embedded in the ground and an end attached to the extension adjacent its upper end.

5. The combination with a tower proper comprising a plurality of legs, diagonal brace members for the legs terminating in substantially the plane of the base of the tower, an adjustable anchoring extension at the lower end of one of said legs, and a ground brace extending from the tower, substantially at said base line and in reverse direction to the adjacent diagonal brace member.

In testimony whereof I affix my signature.

HAROLD O. HILL.
